SWITCH MECHANISM FOR DIRECTION INDICATORS

Francis Thomas Routery, Kingsway, Lambton Mills, Ontario, Canada

Application July 11, 1931, Serial No. 550,070

3 Claims. (Cl. 200—59)

The invention relates to a switch mechanism for direction indicators as described in the present specification and illustrated in the accompanying drawing which forms a part of the same.

5 The invention consists essentially of the novel features of construction pointed out broadly and specifically in the claims for novelty following a description containing an explanation in detail of an acceptable form of the invention.

10 The objects of the invention are to devise a switch mechanism that can be easily attached to the steering column of various makes of cars and which will automatically control the direction indicators mounted on the vehicle through the movements of the vehicle; to furnish a switch that will contain means for giving a pre-warning signal prior to the turning of the vehicle either to the right or to the left as the case may be; to enable the motorist to give his undivided attention to the driving of his vehicle and thereby insure better and safer driving; to construct a switch that will be constantly in readiness for connecting or disconnecting the required signals and free the mind of the motorist from worry in 15 warning other cars or pedestrians of his intentions; and generally to provide an efficient switch for direction indicators of comparatively few parts, easy to install and operate.

20 In the drawing Figure 1 is a plan view of the switch having the cover removed and connected to a steering column of a vehicle.

Figure 2 is a side sectional view of the switch connected to a steering column.

Figure 3 is a cross sectional view of the switch 25 taken on the lines 3—3 in Figure 2.

Figure 4 is a cross sectional view of the switch taken on the lines 4—4 in Figure 1.

Figure 5 is a detail of the switch contact.

Figure 6 is a detail of the interrupter.

40 Like numerals of reference indicate corresponding parts in the various figures.

Referring to the drawing the switch mechanism for operating the direction indicators is in the form of an insulated casing as indicated by 45 the numeral 10 having the collar 11 which is adapted to engage the steering column 12 containing the steering post 13.

The casing 10 has the slot 14 extending into the collar wall 15 and which corresponds to the 50 slotted portion 16 of the column 12 and through which projects a portion of the toothed wheel 17 and which abuts the steering post 13 and is pivotally mounted on the arm 18 and held in position by the screw member 19.

55 The arm 18 is pivotally mounted at one end to

the boss 20 of the casing 10 and at the other end is engaged by a helical spring 21 which forms a buffer for the toothed wheel 17.

5 The pinion 22 and the cam 23 are fixedly secured together and are mounted on the pivot pin 24, the pinion engaging with the toothed wheel 17 and the cam 23 being engaged with the contact posts 25 and 26 which are inserted in the tubular passages 27 and 28 of the casing 10.

10 The contact posts 25 and 26 have the externally threaded ends 29 and 30 engaging with the internally threaded sleeves 31 and 32 having the shoulders 33 and 34 forming abutments for the helical springs 35 and 36 held thereagainst and within the passage by the cap screws 37 and 38.

15 The pivot pin 24 forms the contact to the electrical interrupter 39, the latter having the wire connection 40 to the battery 41 and the ground wire 42 and the connection to the direction indicator lights 43.

20 The contact posts 25 and 26 when not in operation will be free from engagement with the cam 23 but upon the movement of the toothed wheel 17, the cam will immediately rotate and thereby bring the shoulders 44 and 45 of the cam into engagement with either the contact post 25 or the contact post 26 according to the direction in which the vehicle is turning.

25 Upon contact being made between the post and the cam, the electrical connection will immediately be made to one set of lights 43 through either the contact 46 or 47 of the posts 25 and 26, the circuit being completed through the interrupter 39. When the vehicle has made the turn, the cam will be rotated so that the shoulders thereof will disengage with the contact post in operation consequently disconnecting the circuit, and the lights which were previously intermittently flashing will cease.

30 In this way whichever direction the vehicle is about to turn a signal will automatically be given for the right or left turn.

35 The flashing effect is attained through the electrical interrupter 39. This device is really a "flasher" mechanism in itself and is similar to the small flashers used in connection with display counter signs, etc. where it is desired to have lights flash on and off. The small coil in the interrupter is the means whereby the contact is made and broken when the indicator lights are on.

40 In certain cases where it is desired to give a pre-warning signal there is provided in the switch mechanism the pusher posts 55 and 56 which are manually operated and fit in the tubular passages 53 and 54 of the casing 10, the pusher posts 55

having the neck portions 57 terminating in the head recesses 58 for the springs 59 held therein by the screw caps 60.

The neck portions of the pusher posts are 5 adapted to abut the sleeves of the contact arms or posts so that by pressing downwardly on one pusher post or the other it will have the effect of pressing forwardly one of the contact posts into connection with the cam and immediately energize the particular flashing indicators denoting 10 the particular direction in which the vehicle is about to turn.

In neutral position when the vehicle is driven 15 along straight the contact posts 25 and 26 are not in contact with the cam 23. When a corner is turned the shoulder 44 or 45 of the cam 23, depending on whether a right or left hand turn is being made, is brought into contact with either one of the contact posts 25 or 26. In other words 20 there is a clearance in the neutral position between the end of the contact posts 25 or 26 and the cam 23. It will be readily seen that when the cam is rotated, the shoulder portions being larger in diameter, will make contact with the contact 25 posts 25 or 26 depending on whether a right or left hand turn is made. The shoulder portion in the cam is towards the top of the switch mechanism. In other words the normal clearance is taken up by the shoulder portions 44 or 45 upon 30 rotation of the cam.

As hereinbefore stated, it will be seen that the pusher posts 55 and 56 are only used where it is desired to get a pre-warning signal. When either of the pusher posts 55 or 56 are pressed downwardly the contact post 25 or 26 is released and is forced into contact with the cam 23 by the helical spring 35, in other words, when in the neutral or off position, the contact posts 25 and 26 are held in their off position by the shoulders 33 and 34 40 which form an integral part of the threaded sleeves 31 which slide backwardly and forwardly in the groove provided therefor.

Naturally when the pusher posts 55 or 56 are 45 pressed down, the shoulder is released from its position against the pusher posts 55 or 56 and the spring forces the contact posts into engagement with the cam 23. When the turn has been completed the threaded sleeve will be found to have returned to its normal position in engagement 50 with the pusher posts 55 or 56. It will thus be noticed that no resetting of the device is required after making a turn, the operation being entirely automatic.

After the vehicle has made the turn through 55 the movement of the steering post the toothed wheel will rotate the pinion and cam to the off position thereby forcing back the particular contact post from engagement and immediately the flashing signals will be disconnected at the same 60 time the contact post reverting to its normal position will automatically push the manual post up so that both the automatic and manual posts are ready for the next operation.

It will therefore be seen that no matter if the

prewarning signal is not used the automatic posts will operate just the same.

What I claim is:

1. In a switch mechanism for direction indicators, a casing having means for attachment to a steering mechanism, said casing having a pair of horizontal tubular passages and a pair of vertical tubular passages adjacent to the former and having intercommunicating slots between each adjacent horizontal and vertical passage, an arm secured at one end within said casing and spring-held at the other end, a toothed wheel rotatably mounted on said arm and engaging with a rotating part of said steering mechanism, a pinion and cam mechanism in said casing engaging with said toothed wheel, a pair of contact posts spring-held in the horizontal passages of said casing and adapted to be engaged and disengaged by said cam, a pair of manually operated pusher posts spring-held in the vertical passages of the casing and adapted to release the spring-held contact posts for engagement with said cam to give a pre-warning signal.

2. In a switch mechanism for direction indicators, a casing having means for attachment to a steering mechanism, said casing having a pair of horizontal tubular passages and a pair of vertical tubular passages adjacent to the former and having intercommunicating slots between each adjacent horizontal and vertical passage, an arm secured at one end within said casing and spring-held at the other end, a toothed wheel rotatably mounted on said arm and engaging with a rotating part of said steering mechanism, a pinion and cam mechanism in said casing engaging with said toothed wheel, a pair of internally threaded sleeves having shoulders and situated in said horizontal passages, a pair of contact posts having externally threaded ends and engaging said internally threaded sleeves, cap screws closing in the entrances of said horizontal passages, helical springs abutting the shoulders of said sleeves and held thereagainst by said cap screws, said contact posts adapted to be engaged or disengaged by said cam, a pair of manually operated pusher posts spring-held in the vertical passages of the casing and adapted to release the spring-held contact posts for engagement with said cam to give a pre-warning signal.

3. In a switch mechanism for direction indicators, a casing having a collar adapted to engage with a steering mechanism, a gear mechanism in said casing operated by the movement of one part of the steering mechanism, a pinion and cam mechanism connected to an electrical circuit and an interrupter, contact posts automatically connected by said cam through said gear mechanism, manually operated posts adapted to release the contact posts for engagement with said cam, said contact posts adapted to be re-engaged by the manually operated posts through the movements of said gear mechanism.

FRANCIS THOMAS ROUTERY.
